UNITED STATES PATENT OFFICE.

CHARLES ZIMMERMAN, OF FREDERICK, MARYLAND.

DESIGN FOR A SHUTTER-BRACE.

SPECIFICATION forming part of Design No. 29,337, dated September 13, 1898.

Application filed January 3, 1898. Serial No. 665,504. Term of patent 14 years.

To all whom it may concern:

Be it known that I, CHARLES ZIMMERMAN, a citizen of the United States, residing at Frederick, in the county of Frederick and State of Maryland, have invented and produced a new and original Design for a Shutter-Brace, of which the following is a specification, reference being had to the accompanying drawings, forming a part thereof.

10 In the accompanying drawings I have shown my design embodied in a shutter-brace, in which—

Figure 1 is a perspective view, and Fig. 2 is a plan view.

15 The essential features of my design consist in the shutter-brace made the subject-matter of illustration and description.

As illustrated in the drawings, A is a rod-like body having a bent end B extending at

the other end the body gradually bends out of a right line to one side and is bent back upon itself, forming the pear-shaped loop C, extending in a plane at substantially right angles to the plane of the bent end portion 25 B, the end of the bent portion forming the pear-shaped loop terminating near the point where the body of the rod begins to curve to one side to form the pear-shaped loop.

What I claim is—

30 The design for a shutter-brace, substantially as shown and described.

In testimony whereof I have signed my name to this specification in the presence of two subscribing witnesses.

CHARLES ZIMMERMAN.

Witnesses:

ROBT. A. KEMP,
WILLIAM B. STORM.
